ABSTRACT

At the receiving end of a communication system utilizing a lower keying frequency f_1 and a higher keying frequency f_2 for the transmission of information, a counter with $N/2$ stages is stepped by clock pulses having a cadence Nf_2 . The incoming two-frequency wave is converted into a train of signal pulses occurring at the end of each half-cycle, these signal pulses being used to reset the counter which therefore does not generate an output if the signal pulses follow one another at a rate equal to or faster than $1/f_2$. With lower incoming frequencies, the counter sets a flip-flop which is then reset by the next signal pulse and which thereby generates a stepped wave to yield, on integration, a definite DC voltage.

DEMODULATOR FOR TWO-FREQUENCY COMMUNICATION SYSTEM

Our present invention relates to a demodulator for a communication system of the type wherein two keying frequencies are alternately generated to transmit information, e.g. as dots and dashes of the Morse code or as marks and spaces of the Baudot code.

A demodulator used at the receiving end of such a transmission system should be capable of discriminating between two relatively closely spaced keying frequencies in order to reduce the required bandwidth. Conventional demodulators, satisfying this requirement only imperfectly, include limiters, differentiators and rectifiers to derive from the incoming two-frequency oscillation a signal pulse whenever that oscillation goes through zero, the cadence of these pulses thus being double the momentary keying frequency. The signal pulses are used to trip a monostable circuit, or monoflop, whose relaxation time should be as close substituted possible to a half-cycle of the higher of the two keying frequencies so that the ratio between pulses and gaps appearing at the off-normal output is considerably larger for the higher frequency than for the lower one. The usual monoflops, however, have a recovery period approximately equaling their relaxation time so that the pulse-to-gap ratio cannot be much greater than 1 : 1 for the higher of the two keying frequencies.

Thus, if the two keying frequencies are f_1 and f_2 (with $f_1 < f_2$), corresponding to respective cycle lengths or periods $T_1 = 1/f_1$ and $T_2 = 1/f_2$, the magnitudes of the integrated output voltages V_1 and V_2 of the monoflop can be expressed by the relationship

$$V_1/V_2 = (T_1 - 2T/T_2 - 2T) \cdot (T_2/T_1) \quad (1)$$

where T is the relaxation time of the monoflop. If it were possible to make this relaxation time equal to the cadence or recurrence rate $2f_2$ of the signal pulses derived from the higher keying frequency, i.e. if $2T = T_2$, the ratio $V_1 : V_2$ would become infinite. For the aforesaid practical considerations, however, the optimum value realizable for T is approximately $T_2/4$; this value, if substituted in equation (1), yields

$$V_1/V_2 = 2 - (T_2/T_1) = 2 - (f_1/f_2) \quad (2)$$

If the keying frequencies are $f_1 = 390$ Hz and $f_2 = 450$ Hz, the insertion of these values in equation (2) gives a voltage ratio voltage ratio of $V_1/V_2 = 1.15$. This ratio, which is unalterable by amplification, is barely sufficient for positive discrimination between the two specified frequencies so that a larger bandwidth would be needed to ensure the accuracy of transmission.

It is, therefore, the general object of my present invention to provide an improved demodulator for the purpose set forth which discriminates with certainty between closely spaced keying frequencies, provided that the higher one of these frequencies has a known minimum value.

A more specific object is to provide a demodulator of this character which can be realized with integrated circuitry.

A demodulator according to my present invention comprises, like the conventional type of demodulator referred to above, input circuitry for deriving at least one and preferably two signal pulses from each cycle of the incoming oscillation, though more generally the number of such pulses per cycle could be any integer k . A timer measures an interval of $T_2/2$ (expressed in seconds if the frequency is given in Hertz) or, in the more general case, of $T/k = 1/kf_2$, starting with the occurrence of any signal pulse, the timer being resettable by any sufficient signal pulse to restart the measurement of that interval. If such subsequent signal pulse does not occur at or before the end of the measured interval of $1/kf_2$, the timer triggers a pulse generator to produce an output pulse whose duration substantially equals the time difference $1/kf_1 - 1/kf_2$ and which, in the preferred embodiment described in detail hereinafter, may be a flip-flop reset by the next signal pulse so that the length of its output pulses in the presence of keying frequency f_1 equals $(T_1 - T_2)/k$.

According to a more specific feature of my invention, the timer is designed as a pulse counter of N/k (preferably $N/2$)

stages stepped by clock pulses recurring at a cadence of Nf_2 . If this counter is not reset by a signal pulse on or before being fully loaded, its output in response to the next clock pulse triggers the aforementioned pulse generator to indicate that the incoming frequency is lower than f_2 . Since this pulse generator is never triggered with frequencies of magnitude f_2 or greater, its output voltage is invariably zero in the presence of the higher keying frequency and acquires a finite value for any lower frequency differing from the cutoff frequency f_2 by at least k clock cycles. Thus, the ratio N/k determines the resolution of the frequency demodulator.

According to another advantageous feature of my invention, the input circuitry used to derive the signal pulses from the incoming oscillation includes a logic network with one or more inverters to generate a slightly delayed image of the squared oscillation, this oscillation then being logically combined with its delayed image to generate a pulse of a width equaling the delay. The necessary logic gates can be incorporated, along with other elements of the demodulator, in an integrated circuit.

The present invention will become more readily apparent from the following description, reference being made to the accompanying drawing in which:

FIG. 1 is a block diagram of a discriminator embodying the invention;

FIG. 2 is a set of graphs relating to the operation of the system of FIG. 1;

FIG. 3 is a circuit diagram for one of the blocks of FIG. 1;

FIG. 4 is a set of graphs relating to the network of FIG. 3; and

FIG. 5 shows comparative response curves for a conventional demodulator and for the system of FIG. 1.

The demodulator shown in FIG. 1 comprises a timer which includes a clock circuit T, generating a train of pulses with a cadence Nf_2 , which steps a counter CP having $N/2$ stages. Resetting input r of counter CP receives a series of signal pulses P from an input circuit including an amplifier-squarer AS and a logic network RL. Limiting amplifier AS converts an incoming oscillation f into a square wave Q_f from which the logic network RL derives the signal pulses P in a manner more fully described hereinafter with reference to FIG. 3.

The output of counter CP is fed to a setting input p of a flip-flop B whose resetting input o receives the signal pulses P from network RL. Pulses Z appearing in the set output q of flip-flop B are integrated in a low-pass filter PB to generate a direct current voltage V, the latter being compared by a threshold device S with a predetermined reference level. Whenever voltage V exceeds that reference level, circuit S generates an output signal U.

The operation of the system of FIG. 1 will be described with reference to FIG. 2 showing the series of signal pulses P and the output pulses Z of flip-flop B. In the left-hand portion of FIG. 2, thus during an initial transmission interval, the pulses P have a recurrence period equal to $T_2/2$ corresponding to the higher keying frequency f_2 alternating with the lower frequency f_1 in the input oscillation f of FIG. 1. Every pulse P resets the counter CP which therefore returns to zero as soon as it has been fully loaded by the clock pulses from source T, its loading period being equal to the pulse period $T_2/2$. If the incoming frequency should for any reason be higher than f_2 , the counter would prematurely reset to restart the count with each new signal pulse. In neither case, therefore, would an output from the counter reach the setting input p of flip-flop B.

During a transition period T_x , the input frequency is shown to shift from f_2 to f_1 so that the pulse spacing increases beyond $T_2/2$ to a period $T_1/2$ corresponding to a half-cycle of the lower keying frequency. Toward the end of transition period T_x , therefore, counter CP becomes fully loaded and, in response to the next clock thereafter, sets the flip-flop B to generate a first rectangular pulse Z_0 in the output q thereof, this pulse being foreshortened by the occurrence of the next signal pulse P at time t_0 . The following signal pulses, having the spacing

$T_1/2$, allow the full development of output pulses Z whose width equals half coincide difference $T_1 - T_2$ between the two keying-frequency cycles. Each pulse Z is terminated by a pulse P simultaneously resetting the counter CP.

The preferred mode of realization of logic network RL, illustrated in FIG. 3, comprises a chain of four cascaded inverters A_1, A_2, A_3, A_4 for the incoming square wave Q_0 . These inverters, owing to their inherent circuit reactances, introduce a very slight delay (amounting to a small fraction of period $T_2/2$) so that the square-wave outputs Q_1, Q_2, Q_3, Q_4 thereof are relatively staggered as well as inverted, as illustrated in FIG. 4. Original wave Q_0 is logically combined with its delayed and inverted image Q_3 in a NAND gate G_1 producing a train of short pulse gaps P_1 which coincide with the leading edges of wave Q_0 ; waves Q_1 and Q_4 are similarly combined in a NAND gate G_2 to produce analogous pulse gaps P_2 coinciding with the trailing edges of wave Q_0 . A combination of the outputs of NAND gates G_1 and G_2 in a further NAND gate G gives rise to the pulses P delivered to inputs r and o of counter CP and flip-flop B.

Gates G_1, G_2 and G are representative of several logic circuits designed to derive the pulses P from the relatively staggered and inverted square waves Q_0, Q_1-Q_4 .

The number N of clock pulses per cycle T_2 should be large enough to minimize the uncertainty due to the random phasing of the clock pulses with reference to the signal pulses P. Thus, the spacing of these clock pulses determines the maximum separation of two frequencies in the vicinity of f_2 which would permit a full loading of counter CP between successive zero crossings.

Naturally, a change in the number of active counter stages to alter the magnitude of N will accommodate different cutoff frequencies f_2 , the same result could be obtained, of course, by varying the cadence of clock circuit T.

If only the pulse gaps P_1 or P_2 (or their inversions) were utilized, the system would generate only one signal pulse P per cycle so that the number of counter stages would have to be doubled for an otherwise identical mode of operation. The width of these pulse gaps has been exaggerated in FIG. 4, for the sake of clarity.

In FIG. 5 we have shown a comparison between the output voltage $V(t)$ of a conventional demodulator of the type initially described, graph (A), and the same voltage as produced by the system of FIG. 1, graph (B). Curve (a) of graph (A) shows the voltage variation between levels V_1 and V_2 upon a changeover between a higher keying frequency $f_2 = 450\text{Hz}$ and a lower keying frequency $f_1 = 390\text{Hz}$, in conformity with the ratio of 1.15 : 1 given above. Curve (b) of graph (A) shows the same ratio between voltages gV_1, gV_2 amplified with a gain

g ; such amplification, therefore, is without effect upon the signal-to-noise ratio of the system. As illustrated in graph (B), the voltage level V_2 is zero in the presence of frequency f_2 , whereas the voltage level V_1 , due to frequency f_1 , is finite and may be amplified at will to magnitudes $g'V_1, g''V_1$, for the establishment of a desired signal-to-noise ratio.

Reference may be made to commonly owned application Ser. No. 36,252, filed May 11, 1970 by E. Angeleri and F. Balugani disclosing a system for generating such keying frequencies of, say, 390Hz and 450Hz by a selective combination of harmonically related pulse trains.

We claim:

1. In a communication system having means for transmitting information by the alternation of a relatively low keying frequency f_1 with a relatively high keying frequency f_2 , a demodulator for said information comprising:
  - receiving means for an oscillation containing said frequencies f_1 and f_2 ;
  - input circuitry for deriving k signal pulses per cycle from said oscillation, k being an integer;
  - timing means connected to said input circuitry for measuring an interval of $1/kf_2$ from the occurrence of any signal pulse, said timing means being resettable to zero by any subsequent signal pulse for restarting the measurement of said interval;
  - and pulse-generator means connected to be triggered by said timing means upon the end of a measured interval of $1/kf_2$ preceding the occurrence of such subsequent signal pulse for producing an output pulse of a duration substantially equaling the time $1/kf_1 - 1/kf_2$.
2. A demodulator as defined in claim 1 wherein said timing means comprises a source of clock pulses of cadence Nf_2 and a counter for said clock pulses with N/k stages, N being an integer substantially greater than k .
3. A demodulator as defined in claim 2 wherein $k = 2$.
4. A demodulator as defined in claim 3 wherein said circuitry comprises a squarer for said oscillation, inverter means for generating an image of the squared oscillation delayed with reference to the latter by a small fraction of a cycle, and gate means for logically combining said squared oscillation with its delayed image.
5. A demodulator as defined in claim 2 wherein said signal-repeating means comprises a flip-flop settable by the output of said counter and connected to said input circuitry for resetting by the next-following signal pulse.
6. A demodulator as defined in claim 5, further comprising integrating means connected to said flip-flop for receiving the output pulses thereof.
